UNITED STATES PATENT OFFICE.

OLIVER E. BUCKLEY, OF MAPLEWOOD, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

Application filed December 27, 1919. Serial No. 347,773.

To all whom it may concern:

Be it known that I, OLIVER ELLSWORTH BUCKLEY, a citizen of the United States, residing at Maplewood, in the county of Essex and State of New Jersey, have invented certain new and useful Improvements in Signaling Systems, of which the following is a full, clear, concise, and exact description. This invention relates to telegraph systems and more particularly to submarine cable telegraph systems. Its principal object is the provision of a relay arrangement which will introduce in the transmission of signals none of the difficulties commonly introduced by pole changing transmitting relays when operated at high speeds.

In some types of telegraph systems, notably submarine cable systems it is necessary to introduce a pole-changing relay between the sending key and the signaling conductor, it being impracticable to employ the primary transmitting device for impressing signal impulses directly upon the cable on account of the excessive sparking which would occur at the delicate contact points of the transmitter when breaking the relatively large currents necessary for signaling through the cable. For ordinary slow speed signaling the well known electromagnetic polar relay is quite satisfactory. Any relay of the electromagnetic type produces a certain amount of distortion at the beginning and end of each signal impulse, due to the chattering of the relay contacts. For ordinary slow speed signaling this difficulty is not seriously objectionable because the distorted portion represents but a small percentage of the total signal interval. When attempts are made to increase the speed of signaling this difficulty becomes more serious in that the ratio of the distorted portion to the undistorted portion of the signal impulses increases as the speed of signaling increases, the amount of energy transmitted during a signaling period, and consequently the amplitudes of the received signal, are thus reduced. This chattering of the relay contacts furthermore greatly increases the disturbances due to slight inequalities of duplex balance where duplex operation is used.

This invention provides a sending relay for telegraph systems which, so far as the transmitting apparatus itself is concerned, imposes no limitations on the speed at which

telegraphic or other signaling impulses may be transmitted. The invention makes use of a three electrode electric discharge device such as the well known audion or thermionic relay operating by pure electron discharge or similar three element tubes operating with ionized gas, the potential of the grid or control element of the device being regulated by a transmitting key.

A better understanding of the invention may be had from the following description when taken in conjunction with the accompanying drawing in which Figure 1 shows a simplified arrangement for using a vacuum tube device as a relay in the transmission of direct current telegraphic signals. Figure 2 is a modification of Fig. 1 arranged for grounding the line between impulses. Fig. 3 is a modification of Fig. 2 in which space current normally flows through the tube. Fig. 4 shows an alternative arrangement to that shown in Fig. 3. Fig. 5 shows an alternative arrangement for transmitting signals of positive and negative impulses such as are commonly used in cable telegraphy, while Fig. 6 shows a more symmetrical circuit arrangement using two electric discharge devices or vacuum tubes for the transmitting of signals of positive and negative polarity.

Referring now to the drawing and especially to Fig. 1, there is shown a line conductor 4, having the distant end thereof grounded through a suitable receiving apparatus (not shown) and the other end connected with the output circuit of the vacuum tube 6, said output circuit comprising the heated cathode 5, the anode or plate electrode 8 and the grounded battery 9. A leakage path between the plate electrode 8 and the grid electrode 7 is established through the resistance 10 having one terminal thereof connected with the plate electrode 8, the other terminal being connected with the grid electrode 7. There is also connected with the grid electrode 7 a source of potential 12, the positive terminal of which is connected with the heated filament 5. The application of this source of potential to the grid electrode thereby changes the polarity of the charge on this electrode with respect to the heated filament 5 and reduces the space current to zero. When the source of potential 12 is removed from the grid electrode the potential of that electrode is made

positive by the battery 9 acting through the resistance 10, thereby reducing the internal resistance of the tube to the flow of current and permitting current to flow through the 5 tube to the line 4. There is provided in circuit with the source of potential 12 and the grid electrode 7 a key 11 which is for the purpose of controlling the application of this source to the grid electrode and in 10 consequence the current in the output circuit of the tube 6. The impulses composing the various signals as impressed on the line are therefore controlled by the key 11. Thus when it is desired to transmit signals over 15 the line, the key 11 would be depressed for disconnecting the source of potential 12. This thereby renders the tube operative and impresses upon the line an impulse, the duration of which depends upon the length of 20 time during which this key is depressed.

The modification shown in Fig. 2 is substantially the same as that of Fig. 1 with the exception that the line is grounded through the resistance element 13. This 25 ground is for the purpose of forming a path for discharging the line between signal impulses. The resistance element 13, which, as noted, is connected in parallel with the plate electrode 8 and the heated filament 5 30 of the tube 6 serves to regulate the intensity of the impulses applied to the line. In this case, as in the previous one, the tube is normally inoperative and no current flows to the line, but upon the depression of the 35 key 11 the source of potential 12 is disconnected from the grid electrode 7 and a potential is applied to the line through the resistance 13. This resistance, thereby, serves to control the intensity of the impulses 40 applied to the line and also serves to drain the charge from the line between signal impulses.

In Fig. 3 there is shown another embodiment of the invention in which case the 45 source of potential 9 is normally disconnected from the grid electrode 7. Inasmuch as the source of potential 12 is permanently connected with the grid electrode 7 through the resistance 14, this electrode will thus be 50 so charged with respect to the heated filament 5 that space current cannot flow between the electrodes, and the line 15 is normally discharged through the resistance 13. The key 11 upon being depressed connects 55 with the grid electrode 7 a source of potential 9 through the resistance 16, and if the resistances 14 and 16 are properly adjusted with reference to the sources of potential 12 and 9 respectively the potential of the 60 grid electrode 7 will thereby be established at such a value as to permit the desired signaling current to be applied to the line. In this way impulses of different duration may be impressed on the line 15 to represent dots and dashes.

Referring now to Fig. 4 and the particular embodiment illustrated therein, and which is considered as a modification of the arrangement shown in Fig. 3, the key 11 controls the application of both of the sources 70 of potential 9 and 12 respectively to the grid electrode 7. The source of potential 12 is normally connected with the grid electrode 7 through the key 11, and thus charges this electrode negatively with respect to the heated filament 5 and no space current will flow between the filament 5 and plate 8. When the key 11 is depressed the source of potential 12 is disconnected from the grid electrode and the source 9 connected thereto. 80 The connection of this source of potential with the grid electrode changes the charge thereon from negative to positive with respect to the heated filament 5 and permits space current to flow through the tube to 85 apply to the line a definite potential.

It is thus seen that the signaling is effected by means of the key 11 and if it is desired to send impulses of various characters the key 11 will be actuated for applying current to the line in accordance with the character to be transmitted. The line is, however, grounded between the signal impulses through the resistance 19 which provides a discharge path for the current in the 90 conductor 17 at the instant the key 11 is released.

In submarine cable signaling the various characters are generally formed of positive and negative impulses, and in Fig. 5 there 100 is shown an embodiment whereby such signals may be transmitted over a signaling conductor. In this figure there is shown a portion of the cable 18 having a conductor 22 connected to the vacuum tube 6 and the 105 resistance 13 through the condenser 23. The condenser 23 is the common sending condenser well known to those skilled in the art. Its purpose is to reduce the distortion of the 110 signal impulses received at the distant end. The resistance 24 is equipped with three 115 movable contact points 25, 26 and 27. The batteries 9 and 12 are connected with the grid electrode 7 through portions of the resistance 24 allowing current to flow through the 120 resistance 24 thereby establishing a potential gradient along that resistance. The point 26 is so adjusted that a definite space current will flow through the vacuum tube, thereby establishing a normal potential difference between the terminals of the 125 resistance 13. The tongue or contact maker 28, which may form a part of an automatic transmitting apparatus, is adapted to be moved either to the left or right for the purpose of including with or excluding from the grid electrode a portion of the resistance 24. Contact makers of automatic transmitters do not have the tendency to chatter which is present in the ordinary transmitting pole- 130

changing relays. This key, therefore, provides means whereby the potential on the grid electrode may be varied for the purpose of transmitting over the line or cable 5 pure impulses of negative or positive polarity by increasing or decreasing the current through the resistance 13.

In transmitting a signal, assuming it is desired to send a signal of positive polarity, 10 the tongue 28 would be moved to the right for engaging the contact associated with contact member 25. This short-circuits a portion of the resistance 24 and connects the source of potential 9 with the grid electrode 15 7 through the remainder of this resistance and consequently increases the space current through the tube 6 and increases the potential applied to the terminals of the condenser 23. The sending of impulses of negative 20 polarity is accomplished in the same manner except that the tongue 28 is moved to the left for engaging the contact member 27. This connects the battery 12 with the grid electrode 7 through a smaller portion of the 25 resistance 24 than was in the previous case. In this way the grid electrode 7 is charged more negatively with respect to the heated filament 5 and thereby impresses upon the line 22 an impulse of negative polarity. The 30 positive and negative impulses can be made to possess the same amount of energy by properly adjusting the contact members 25 and 27 on the resistance 24.

It is thus seen that a vacuum tube is not 35 only adapted for use in the transmission of dots and dashes, but may also be employed for the purpose of transmitting characters composed of positive and negative impulses.

Referring now to Fig. 6 there is shown a 40 symmetrical circuit arrangement comprising two electric discharge devices or vacuum tubes of the audion type such as 29 and 30. These devices as before are provided with the usual electrodes designated by the 45 numerals 5, 7 and 8. The grid electrodes 7 of these tubes are connected with the battery 31 through the high resistance units 32 and 33 respectively, and are each thereby given a negative charge sufficient to reduce the 50 space current to zero.

When the key 34 is moved to make contact with the point 35, the positive pole of battery 38 is connected by way of resistance 37 to the grid 7 of the vacuum tube 29. The 55 potentials of the batteries 31 and 38 and the values of resistances 32 and 37 are so chosen that under this condition the potential of the grid 7 with reference to the filament 5 will be made positive, that is the positive 60 potential applied by the battery 38 more than overcomes the negative potential applied from the battery 31 and permits current to flow in the output circuit of the vacuum tube 29 from battery 38 through resistance 41 in the direction of the arrow, 65

through the vacuum tube 29 from the plate 8 to the filament 5 and back to the other pole of battery 38. This flow of current through the resistance 41 gives the line conductor 42 a positive potential with respect to ground 70 and causes a positive impulse to flow to line.

When the key 34 is moved into contact with the point 36, the grid electrode 7 of the vacuum tube 30 is made positive with respect to its filament 5 and current flows 75 through the resistance 40 in the output circuit of the vacuum tube 30 in the direction of the arrow. This flow of current in the resistance 40 gives the line conductor 42 a negative potential with respect to ground 80 and consequently a negative impulse flows to the conductor. In the intermediate position of the key 34, as shown in the drawing, the line conductor 42 is grounded through the resistances 41 and 40 so that any accumulated charges on the cable conductor can be drained off to ground. It is desirable that the resistances 32 and 33 be fairly high so that the circuit from battery 38 through key 34, contact 35, resistance 37, resistance 85 32, battery 31, filament 5 back to battery 38, or the corresponding circuit through the resistances 39 and 33, will have a minimum shunting effect on the current flowing through the output circuit of the vacuum 90 tube 29 or the vacuum tube 30 as the case may be. It is thus seen that the arrangement in Fig. 6 is well adapted to send symmetrical positive and negative impulses at 95 high speed over a cable conductor.

What is claimed is:

1. Terminal signaling apparatus for a cable or line for impressing upon said cable or line at any instant potential of one of at least two operating values whereby signaling impulses of either polarity and in any desired sequence may be transmitted, said apparatus comprising the combination with a local source of direct signaling potential, of high impedance space discharge means 105 in circuit with said source, control means for said space discharge means, circuit making and breaking means in circuit with said control means for directly associating said signaling potential with said control means, and means including said circuit making and breaking means for impressing at any instant upon said control means potential of 110 one of at least two operating values.

2. Terminal signaling apparatus for a cable or line for impressing upon said cable or line at any instant potential of one of at least two operating values whereby signaling impulses of either polarity and in any desired sequence may be transmitted, said apparatus comprising the combination with a source of direct potential, of high impedance space discharge means in circuit with said source, control means for said 120 space discharge means, circuit making and breaking means in circuit with said control means for directly associating said signaling potential with said control means, and means including said circuit making and breaking means for impressing at any instant upon said control means potential of 125 one of at least two operating values.

- breaking means in circuit with said control means having two fixed contacts, and means including said circuit making and breaking means for impressing at any instant upon 5 said control means potential of one of at least two operating values, the said two last-mentioned values of operating potential being applied when the circuit is completed through said fixed contacts respectively.
- 10 3. Terminal signaling apparatus for a cable or line for impressing upon said cable or line at any instant one of three operating potential values whereby signaling impulses of either polarity and in any desired sequence 15 may be transmitted, said apparatus comprising a local source of direct potential, high impedance space discharge means in circuit with said source, control means for said discharge means, circuit making and 20 breaking means in circuit with said control means, and means associated directly with said circuit making and breaking means, and including a second local source of potential for impressing upon said control 25 means at any instant one of three operating potential values.
4. Terminal apparatus for a cable or line having large distributed electrostatic capacity for impressing upon said cable or line 30 at any instant one of at least two operating potential values whereby signaling waves of either polarity and in any desired sequence may be transmitted, said apparatus comprising a local source of direct potential, a high 35 impedance space discharge means in circuit with said source, a control means for said discharge means, circuit making and breaking means in circuit with said control means, and means associated with said circuit 40 making and breaking means, and including a second local source of potential, for impressing upon said control means at any instant one of at least two operating potential values.
- 45 5. The combination with a cable or line, of a local source of signaling direct potential, space discharge means in circuit with said source, means for controlling the impedance of said space discharge means, a 50 signaling key for controlling said space discharge controlling means and having at least two operating positions in one of which no current will flow through said space discharge means and in the other of which signal 55 impulses will be impressed upon said line or cable, and means having substantially no reactance at signaling frequencies for associating said source of potential with said cable or line, whereby the signaling impulses impressed thereon are substantially 60 rectangular in form.
6. In a high speed submarine cable system, the combination with a cable, of means for transmitting signals at such high speed 65 that the chatter produced by the tongue of

the pole changing relay ordinarily employed for cable transmission would introduce a high frequency disturbance of a prohibitive value, a space discharge relay at the transmitter in place of said ordinary pole changing relay, said space discharge relay comprising an anode, a cathode and a control element, a local source of signaling potential controlled by said space discharge relay, means for associating said source with said cable having negligible reactance at signaling frequencies, and a signaling key at the transmitter associated with said control element and having at least two operating positions whereby substantially rectangular 80 signaling impulses are impressed upon said cable.

7. A circuit for direct current signaling impulses comprising a line or cable, a transmitting battery associated therewith, a high 85 impedance space discharge device through the output circuit of which current from said battery may flow, a controlling element for controlling the amount of current flow through the output circuit of said discharge 90 space, and a signal key or circuit making and breaking device substantially free from contact chatter conductively in circuit with said controlling means for impressing the battery potential upon the control element 95 and transmitting signaling impulses from the output circuit of the space discharge device to the line without substantial change in frequency.

8. The combination with a cable or line, 100 of a local source of transmitting potential connected with said cable or line, a resistance in shunt relation to said line with respect to said source of potential, a high impedance space discharge device in circuit 105 with said source of potential and said resistance, a control element for controlling the space discharge current, and a signaling key or circuit making and breaking device substantially free from contact chatter for controlling said control element.

9. The combination with a signaling line or cable having large distributed electrostatic capacity, of a local source of transmitting potential, means having negligible 115 reactance at signaling frequencies associating said source with said line or cable, a high impedance space discharge device for controlling current flow from said source and having an anode, a cathode and an 120 impedance control element, and a key or circuit making and breaking device substantially free from contact chatter controlling said impedance control element.

10. The combination with a signaling 125 conductor or line having large distributed electrostatic capacity, of a source of direct potential for impressing direct current impulses on said line or cable, high impedance space discharge means for controlling flow 130

- of current from said source to said cable, and a signaling key or circuit making and breaking device relatively free from contact chatter for impressing positive impulses 5 when in one position upon said line or cable and negative impulses when in a second position.
11. Terminal signaling apparatus for a cable or line for impressing thereupon at 10 any instant potential of one of at least two operating values, whereby signaling impulses of either polarity and in any desired sequence may be transmitted, said apparatus comprising the combination with a source 15 of direct potential, of two high impedance space discharge means in opposed relation in circuit with said source, control means for each of said space discharge means, circuit making and breaking means in circuit 20 with said control means, and means associated with said circuit making and breaking means and potential source for impressing at any instant upon one of said control means potential of one of at least two operating values and upon the other of said 25 control means potential of another of said last-mentioned operating values.
12. A signaling system comprising a line, a pair of space discharge relays associated 30 with said line, means adapted when operated in one manner to render one of said relays operative for transmitting direct current telegraph signals of a certain character over said line and when operated in a different manner to render the other of said 35 relays operative for transmitting over said line direct current telegraph signals of a different character.
13. A signaling system comprising a line, a first and a second space discharge tube for 40 applying potentials of different polarities to said line, and means for rendering one or the other of said space discharge tubes operative for transmitting direct current telegraph signals over said line.
14. A signaling system comprising a line, a pair of space discharge tubes each having 45 a control electrode, a source of signaling potential, and means operative for conductively connecting said source of potential with the control electrode of one or the other of said tubes for rendering such tube operative for transmitting direct current telegraph signals over said line.
15. A signaling system, comprising a line, two repeaters of the audion type, a source 50 of signaling potential, a transmitting key operative for associating said source of po-
- tential with either of said repeaters for rendering said associated repeater operative for 55 transmitting direct current telegraph signals over said line.
16. In a signaling system, a line conductor, a symmetrical circuit arrangement comprising a pair of repeaters of the audion type, 60 a source of signaling potential, and means for rendering one or the other of said repeaters operative for transmitting over said line direct current impulses of equal intensity and wave form.
17. In a signaling system, a line conductor, a pair of repeaters of the audion type, a source of signaling potential, means for associating said source of potential with either of said repeaters for rendering said 70 repeaters operative for the transmission of signals over said line, consisting of both positive and negative direct current impulses of equal intensity and wave form.
18. In a submarine signaling system, a line conductor, a pair of vacuum tubes each having a filament, a control electrode and a plate electrode, means for normally rendering said tubes inoperative by maintaining each grid electrode negative with respect 75 to corresponding filament, a source of signaling potential adapted to be connected with the control electrode of either of said tubes, a key for rendering one or the other of such tubes operative by connecting said 80 source of potential with said control electrode thereof for the transmission of desired signals.
19. A signaling system comprising a line, two similar electric discharge devices, each 85 containing control electrodes, and oppositely associated with said line, and means whereby direct current telegraph signals applied to the control electrodes renders one of said devices operative for transmitting 90 signals of one sign to the line, and the other responsive to the transmitting signals of the opposite sign.
20. A signaling system comprising an electrically long signaling conductor, a first 105 and a second vacuum tube conductively connected to said line for applying potentials of different polarities thereto, and a key effective in two positions for rendering one or the other of said tubes operative for 110 transmitting direct current telegraph signals over said line.
- In witness whereof, I hereunto subscribe my name this 23rd day of December A. D., 1919.
- OLIVER E. BUCKLEY.
